UNITED STATES PATENT OFFICE

132,020

DESIGN FOR A BAKE PAN

Joseph G. Jackson, Oak Park, Ill., assignor to
The Edward Katzinger Company, Chicago, Ill.,
a corporation of Illinois

Application June 24, 1940, Serial No. 93,212

Term of patent 7 years

To all whom it may concern:

Be it known that I, Joseph G. Jackson, a citizen of the United States, residing at Oak Park, in the county of Cook and State of Illinois, have invented a new, original, and ornamental Design for a Bake Pan, of which the following is a specification, reference being had to the accompanying drawing, forming a part thereof.

Fig. 1 is a top plan view of a bake pan, partly broken away, showing my new design. The bake pan is shown with an outer rim portion in dotted lines to indicate a continuation of the outer rim portion in full lines. A plurality of

pairs of concentric circular dotted line portions indicate rim portions of cup elements corresponding to the rim portion of the cup element shown in full lines, said cup elements each having a central area of conventional design.

Fig. 2 is an enlarged fragmentary sectional view taken on line 2—2 of Fig. 1.

The dominant feature of the design resides in the portion shown in full lines.

I claim:

The ornamental design for a bake pan, as shown and described.

JOSEPH G. JACKSON.
